UNITED STATES PATENT OFFICE.

ALLEN J. FELLER AND JOHN O. WATTERS, OF DUCHESNE, UTAH.

SPRING-BENDING MACHINE.

Application filed February 18, 1921. Serial No. 445,915.

To all whom it may concern:

Be it known that ALLEN J. FELLER and JOHN O. WATTERS, citizens of the United States, residing at Duchesne, in the county 5 of Duchesne and State of Utah, have invented new and useful Improvements in Spring-Bending Machines, of which the following is a specification.

This invention relates to certain new and 10 useful improvements in spring bending machines and the primary object thereof is to provide a machine of this type which is of simple and economical construction and which has novel means for effecting bending 15 of the spring.

The invention further aims to provide a machine of this type which can be operated to impart varying curvatures to the springs and to otherwise improve, simplify and reduce 20 to a minimum the number of parts required to provide an effective and easily operated machine of this type.

Further and other objects will be later set forth and manifested in the course of 25 the following description.

In the drawings:

Figure 1, is a fragmentary side elevation of the invention;

Figure 2, is a top plan view;

Figure 3, is an enlarged section on line 30 3—3 of Figure 1, and

Figure 4 is a similar view on line 4—4 of Figure 2.

In proceeding in accordance with the 35 present invention, a frame is employed consisting of a horizontal looped member 1 which may be formed of a strip of metal set on edge and bent into loop form as shown. Suitable legs 2 and braces 3 are 40 employed to afford a substantial mounting for the frame.

A pair of similar holders are employed 45 each embodying a U-shaped member, the arms 4 of which are arranged to extend upwardly and the base of which seats on top of the frame 1 and has a downwardly extending guide 5 which is slidably received in the space between the sides of the looped frame. An abutment 6 is employed which 50 engages the bottom of the frame 1. A screw 8 loosely engages through abutment 6 and is threaded into the base of the holder and has an eye 9 so that a rod or bar can be passed through the eye and the latter rotated to securely clamp the holder in any 55

desired position along the length of the frame.

The arms of the holder have spaced perforations 10 to receive a pin 11, the latter formed to be passed through the eyes E at 60 the ends of the spring support S.

The bending device includes an inverted U-shaped base 12 the arms of which embrace and are rigidly secured to the frame sides by suitable fastenings 13 and which is 65 formed with a depending nut part 14 to receive a screw 15 having a hand crank 16, the upper end of the screw having a reduced terminal forming a shoulder, the terminal extending through apertures in the flexible 70 spring support S and in the spring T, the support S seating on the shoulder.

In operation, the spring T is heated and 75 clamped by means of clamps, not shown, onto the support S, the latter being secured to the holders by passing the pins 11 through the eyes E, the terminal 17 being

projected through the apertures at the center of the spring and the spring support. By turning the screw 15 the desired curvatures may be imparted to the spring support and thereby to the spring. When the desired bend has been imparted to the spring support, the latter is then held rigid or in fixed position, by clamping the holders to 80 the bed or frame 1 until the spring becomes set. From the foregoing it will also be seen that the arms 4, will act as guides or aliners for the ends of the spring support, preventing lateral movement thereof. 90

The openings 10 also provide for the accommodation of clamps with which some springs are equipped since in such instances the spring ends must be supported 95 higher up to provide room for the clamps above the frame.

What is claimed is:

1. A spring bending machine, including a frame of looped formation, supporting feet therefor, an inverted U-shaped member straddling the center of the frame and having its arms rigidly secured to the frame sides, a nut borne by said member and arranged in the space between the frame sides, a screw threaded through the nut and having a reduced upper terminal to receive a central hole in the spring, a pair of holders borne by the frame and including U-shaped members seating on top of the frame and the arms of which have spaced alined per- 110

forations, a curved spring support having eyes at its ends, a pin for reception in the end eyes of the support extending through the perforations, the bases of the holder members having guides received in the space between the sides of the frame, abutments engaged with the bottom of the frame and having guides engaged in the space between the frame sides, and screws extending through the abutments and threaded into the bases of the holder members to clamp the latter adjustably to the frame.

2. In a spring bending machine, a frame composed of a strip bent to have spaced sides and connected ends, a member seated on the frame and having a threaded opening, a screw extending through the opening and between the frame sides, spring engaging means, U-shaped holders on the top of the frame for the ends of said means, abutments beneath the holders engaged with the bottom of the frame, and screws extending between the frame sides and through the abutments and into the holders to clamp the latter onto the frame.

3. In a spring bending machine, a frame

composed of a metal strip set on edge and bent into loop form with spaced sides and connected ends, supports for the strip, a spring form, a member at the center of the frame bridging the space between the sides thereof, a screw engaging the form and threaded through the member and arranged in the space between the frame sides, holders seated on the top edges of the frame sides, abutments engaged with the bottom edges of the frame sides, the holders and abutments having parts engaging the frame sides to prevent lateral movement thereof, means to secure the form ends to the respective holders, and screws extending through the space between the frame sides and connected to the abutments and holders to clamp the latter to the frame.

In testimony whereof we have hereunto set our hands in presence of two subscribing witnesses.

ALLEN J. FELLER.
JOHN O. WATTERS.
